MOTION PICTURE CLAW FEED APPARATUS

William Smith and James Charles Hall, London,
and James Bernard Barton, Surrey, EnglandApplication October 19, 1936, Serial No. 106,480
In Great Britain October 21, 1935

5 Claims. (Cl. 88—18.4)

The present invention relates to improvements in cinematographic apparatus, more particularly of the type in which a number of individual pictures are viewed in kinematograph sequence; that is to say, at short time intervals relatively to one another.

According to the present invention a picture is projected step by step past a viewing aperture by means of one or more feed pins moving in a closed path, during part of which the pins are positively driven from a hand crank and during part of which by a spring, the operating energy of which is stored in the spring during said positive drive period.

The invention is more particularly described with reference to the accompanying drawing in which:—

Figure 1 is a sectional elevation of one form of construction of device with the cover open.

Figure 2 is a corresponding plan view.

Figure 3 is a sectional elevation of a further form of construction.

In the construction shown in Figures 1 and 2, a strip 1 of paper or the like flexible material, rolled upon itself, as shown at 2, is adapted to be received within the partly circular recess in a casing formed by a bent strip of metal 3. An extension 4 on the strip of metal 3 forms a surface over which the paper strip or the like can be drawn. The paper strip has pictures 5 disposed thereon in spaced relationship and is provided along the edges thereof with perforations 6, into which said pins or claws 9 are adapted to extend so that the strip can be fed past a window aperture 7 in a cover plate 8. Claws or pins 9 are mounted on a supporting device in the form of a plate 19 which is pivotally mounted on a spindle 11. The spindle is supported between the coiled ends of a pair of spring arms 10, the ends of which engage the plate 19. The opposite ends of the spring arms 10 are secured to the base 12 of the apparatus by screws 13 or the like. Other spring means, as for instance a leaf spring, may be employed in place of the spring arms 10. The plate 19 is provided with open notches or abutments 50 with which an offset crank arm 51 is adapted to periodically engage. The crank may be conveniently formed of a strong piece of wire extending through perforations in the side walls of the 14, 15 of the apparatus, and provided with a handle 16. The notches or abutments 50 open toward the claws 9 and thus toward the picture strip. It will be particularly noted that the pivotal axis of the crank in the side walls of the apparatus is disposed below the claws 9 and sub-

stantially midway between the limits of movement of the plate 19. The pivotal axis of the crank is located a slightly lesser distance below the claws 9 than the abutment 50 when the claws are in engagement with the strip.

By this construction, it will be seen that when the handle 16 is turned in a clockwise direction, the crank arm 51 will engage the open notches or abutments 50, as shown in full lines in Figure 1, and draw down the claws 9 out of engagement with the picture strip. Further rotation of the crank in the same direction shifts the plate 19 against the action of the coiled ends of the spring arms to the position shown in dotted lines in Figure 1 wherein the claws 9 are in position to re-engage the paper strip. The spring arms 10 operate to force the claws 9 into re-engagement with the paper strip and further rotation of the crank will bring the arm 51 thereof out of range of the notches or abutments 50 so that the stored up energy in the spring arms 10 will serve to rapidly displace the plate 19 and claws 9 to their advanced positions, as shown in full lines in Figure 1, thus advancing the picture strip. A buffer 60 or the like may be employed to arrest the advancing movement of the plate 19. It will be seen that the spacing of the notches or abutments 50 from the claws 9 is greater than the distance of the nearest point on the arc of a circle swept out by the crank arm 51 to the picture strip, so that during this rapid forward movement of the claws 9, no restraint on this movement is presented since the crank arm 51 is completely out of engagement with the notches 50.

The movement of the claws 9 from the position shown in dotted lines in Figure 1 to the position shown in full lines is preferably braked somewhat toward the end of this movement by disposing the upper portion 4 of the casing in an arcuate curve which is adapted to frictionally engage the end of the plate 19 during its movement. Leaf springs 17, 18 are provided on the casing so as to afford frictional resistance to the accidental return of the strip, and to further afford resistance to the accidental shooting forward of the strip so as to thus avoid tearing thereof at the perforations.

It will be appreciated that there is no necessity to reel up the paper strip upon any bobbin since it can be rolled upon itself and slipped elastically into the recess formed by the cylindrical portion of the casing 3.

In the modified form of the invention shown in Figure 3, the claws 32 which are adapted to

engage the picture strip, are connected upon one end of a lever 33 having a pin and slot connection 34 with a spindle 35 mounted in the sides of the casing. A similar crank is pivotally mounted in the side of the casing and has an offset crank arm 36 which engages with a similar open notch or abutment on the lever arm. Springs 38 and 39 cooperate to normally urge the lever 33 in a direction for engaging and feeding the picture strip. A gravity snail cam of rubber or the like 40 is pivoted to the casing and allows the strip to be moved past the same, but prevents any accidental back feeding of the strip.

Operation of the crank in this form of the invention serves to force the crank arm 36 into engagement with the notch on the lever so as to withdraw the claws from engagement with the strip and shift the lever rearwardly to a position wherein the springs 38 and 39 cooperate to urge the claws into engagement with the strip and to advance the same in its feeding direction.

From the foregoing description, it will be seen that the present invention provides an apparatus wherein a crank operates against the action of spring means for disengaging the claws from the picture strip and for retracting the claws to a position for further engagement with the picture strip, and wherein the spring means serve as the sole means for effecting re-engagement of the claws with the picture strip and for advancing the picture strip, the crank having no part in the feeding cycle of the operation.

It is to be clearly understood that minor changes in the detail of construction and arrangement of parts may be made without departing from the scope of the invention as set forth in the appended claims.

We declare that what we claim is:

1. A claw feed apparatus for a motion picture strip having perforations, comprising guiding means for the picture strip, claws adapted to engage the perforations in the picture strip for advancing the same, a supporting device for said claws movable between advanced and retracted positions, spring means operating on said supporting device for effecting engagement of said claws with the picture strip and for advancing the supporting device to feed the picture strip, means providing an abutment on said supporting device, and a crank pivotally mounted substantially midway between advanced and retracted positions of said supporting device and having a crank arm engageable with said abutment when said claws are in engagement with the picture strip at their advanced position for withdrawing said claws from engagement with the picture strip and for shifting said supporting device against the action of said spring means to a retracted position for re-engagement of said claws with the picture strip.

2. A claw feed apparatus for a motion picture strip having perforations, comprising guide means for the picture strip, claws adapted to engage the perforations in the picture strip for advancing the same, a supporting device for said claws movable between the advanced and retracted positions, spring means operating on said supporting device for effecting engagement of said claws with the picture strip and for advancing said supporting device and the claws carried thereby to feed the picture strip, means providing an abutment on said supporting device, a crank pivotally mounted substantially midway between the advanced and retracted positions of said supporting device and having a crank arm so disposed that a distance

between the picture strip and the nearest point on an arc swept out thereby is less than the distance between said abutment and the picture strip, said crank arm being thus engageable with said abutment when said claws are in engagement with the picture strip at their advanced positions for withdrawing said claws from the picture strip and for shifting said supporting device against the action of said spring means to a retracted position for re-engagement of said claws with the picture strip.

3. A claw feed apparatus for a motion picture strip having perforations, comprising a casing, guide means for the picture strip, claws adapted to engage the perforations in the picture strip for advancing the same, a supporting device for said claws movable between advanced and retracted positions, spring means having one end thereof secured to said casing and having the opposite end thereof connected to said supporting device, a pivot for said supporting device carried by an intermediate portion of said spring means, said spring means operating on said supporting device to urge said claws into engagement with the picture strip and to shift said supporting device about its pivot from retracted to advanced positions whereby to feed the picture strip, means providing an abutment on said supporting device, and a crank pivotally mounted substantially midway between advanced and retracted positions of said supporting device and having the pivotal axis thereof disposed between the picture strip and said pivot and slightly above said abutment, said crank having an offset crank arm engageable with said abutment when said claws are in engagement with the picture strip at their advanced position for withdrawing said claws from the picture strip and for shifting said supporting device against the action of said spring means to a retracted position for re-engagement of said claws with the picture strip.

4. A claw feed apparatus for a motion picture strip having perforations, comprising a casing, guide means for the picture strip, claws adapted to engage the perforations in the picture strip for advancing the same, a supporting device for said claws, a pivot on which said supporting device is mounted, a pair of springs having one end of each secured to said casing and having an intermediate portion of each coiled around said pivot to support the same, the opposite ends of said springs being connected to said supporting device and operating against said supporting device to shift the same on said pivot from retracted to advanced positions whereby to feed the picture strip, the portions of said springs between said pivot and the casing operating to normally elevate said supporting device to maintain said claws in engagement with the picture strip, means providing a notch on said supporting device opening toward said claws and disposed above said pivot, a crank pivotally mounted in said casing and having the pivotal axis thereof disposed above said notch and substantially midway between advanced and retracted positions of said claws, and said crank having an offset crank arm engageable with said notch when said claws are in engagement with the picture strip at their advanced position for withdrawing the claws from the picture strip and for shifting said supporting device against the action of said spring to a retracted position for re-engagement of said claws with the picture strip and for disengagement of said crank arm from said notch.

5. A claw feed apparatus for a motion picture

strip, having perforations, comprising a casing, 5
guide means for the picture strip, claws adapted 10
to engage the perforations in the picture strip for
advancing the same, a supporting device having
a substantially vertical arm carrying said claws
and movable between advanced and retracted positions,
a pivot pin mounted in said casing, said 15
supporting device having a substantially horizontal slot
through which said pivot pin extends,
a spring connected to said casing and having the
free end thereof bearing against said supporting
device between said pivot pin and said arm 20
whereby to normally urge said claws into engagement
with the picture strip, a second spring se-
cured to a portion of said casing and connected
to said supporting device on the opposite side of
said pivot pin for shifting said supporting device 25
and the claws carried thereby from a retracted
to an advanced position whereby to feed the picture
strip, means providing an abutment on said
supporting device below said claws, and a crank
pivotally mounted in said casing and having the 30
pivotal axis thereof disposed above said supporting
device and substantially midway between advanced
and retracted positions of said claws, said
crank having an offset crank arm engageable with
said abutment when said claws are in engagement 35
with the picture strip in advanced position
for withdrawing the claws from the picture strip
and for shifting said supporting device against
the action of said springs to a retracted position
for re-engagement of said claws with the picture 40
strip. 15
